UNITED STATES PATENT OFFICE

CHARLES K. DUNLAP, OF HARTSVILLE, SOUTH CAROLINA

WINDING MACHINE

Application filed May 18, 1930. Serial No. 272,078.

- This invention relates to winding machines, and more particularly to the class of these machines employing a plurality of thread cop supporting mandrels, each of which is mounted to swing about an axis from one position in which the thread is wound thereon, to another position in which the loaded cop may be removed and an empty one substituted.
- 10 Means have been provided for automatically gripping the inner surface of the cop when the mandrel is turned to winding position, and automatically releasing the cop when the mandrel is turned to doffing position. Generally, this has been accomplished by a cam located at the pivot point of the mandrel, which moves a sliding member along the stem thereof as it is swung around, the sliding member being operatively connected to the gripping mechanism.
- 15 The object of the invention is to provide a cop gripping mechanism for engaging the inner surface of the cop with an even grip all around, so as to prevent distortion or 20 loosening of the cop, which will be quick and convenient in operation, and superior to devices of this character heretofore devised.
- 25 Other objects and features of novelty will be apparent as the following description proceeds, as taken in connection with the accompanying drawings, in which:

Figure 1 is a diagrammatic elevation of a portion of a winding machine, showing only so much thereof as is necessary for an understanding of the present invention;

Figure 2 is an end elevation of the structure shown in Fig. 1;

Figure 3 is an enlarged detail view, partly in section showing the improved spindle for supporting conical cops;

Figure 4 is a section taken along the line 4-4 of Fig. 3;

Figure 5 is a view similar to Fig. 3, showing the arrangement for supporting a tubular cop;

Figure 6 is a cross section along the line 6-6 of Fig. 5;

Figure 7 is a view similar to Fig. 5 showing a modified form of the structure;

Figure 8 is another modification of the structure shown in Fig. 5; and

Figure 9 is an elevation of the structure shown in Fig. 8.

Referring more particularly to the drawings, the type of winding machine to which the present invention relates, such as shown in Figs. 1 and 2, is provided with a frictional driving drum 10. A spindle 11 is journaled on a stem 12 mounted above the winding drum. The stem 12 is carried by a pivoted arm 13, which in the form shown in Fig. 1, is provided with a collar 14, keyed to a rotatable shaft 15 parallel to the axis of the driving drum 10. The arm 13 is provided with a weight 16 to cause the spindle 11 to bear upon the friction drum 10 so that the movement of the drum will drive the cop carried by the spindle. The thread or yarn to be wound is supplied from below through a suitable thread guide indicated generally at 17.

As shown in Figure 2, the shaft 15 is provided with another arm 22 which is connected thereto by means of bracket 21, pin 20, and clamp 94. Clamp 94 is fixed to shaft 15 by means of the set screw 95 and is provided with the counterweight 96 to balance the arm 22 and its operating rod 23. The rod 23 is provided with a handle 24 and the lower edge thereof is serrated so as to adjustably receive an abutment member 25.

With the arrangement described above, it will be obvious that when the operator desires to disengage the spindle from the driving drum, he may pull on the handle 24 until one of the serrations will engage the abutment 25. This operation, through the members 22, 21 and 20, will rock the shaft 15 and thus lift the arm 13 and the spindle carried thereby to the position shown in dotted lines in Fig. 2.

The spindle end of the arm 13 is bifurcated as at 26 to receive an enlarged end 27 of the stem 12 which is pivoted therebetween, and when the spindle is raised to the position shown in Fig. 2, the stem may be swung outwardly to the position shown in dotted lines, so that the cop may be manually removed.

The arrangements for releasing the cop as

the spindle is thrown outward are shown in detail in Figs. 3 and 4. An arm 30, similar to the arm 13, is provided with a journalled end 31 about which the arm pivots, and the 5 other end is bifurcated as at 32. A weight 33 is mounted intermediate the ends of the arm 30. The stem 34 is provided with an enlarged end 35 pivoted on a pin 36 carried between the bifurcations 32. The enlargement 35 is generally circular, but is expanded 10 opposite the stem 34, and depressed to form a seat 37 which receives the rolled end of a spring member 38 adjustably secured on the arm 30 by means of a bolt 39 passing through 15 an elongated slot in the spring 38.

The greater part of the stem 34 is of the reduced diameter shown, and upon this reduced portion is journalled the rotatable spindle 40. The spindle is generally cylindrical, with a conical outer end as at 41, and 20 an enlarged frusto conical base 42. The metal of the spindle is cored or cut away intermediate its ends, leaving the bearing portions 43 and 44 at its respective ends. A washer 45 25 is located between the base 42 and the shoulder 46 formed by the reduced portion of the stem 34, and the spindle 40 is held on the stem by a washer 47 secured in place by a screw 48.

30 Mounted on the spindle 40, and outwardly inclined therefrom, are a plurality of spring members 50, each having at its outer end a spur 51 for engaging the inner surface of a cop 52 carried by the spindle. In the form 35 shown, the members 50 are secured to the spindle at its frusto conical base, and are preferably integral with an annular ring 53 which is secured to the base 42.

It will be apparent from an inspection of 40 Fig. 3 that the spring members 50 are normally expanded in a position in which the points 51 penetrate the cone, and furthermore, that this penetration is in the direction which tends to pull the cone onto the spindle, 45 rather than to push it off. Furthermore, it will be apparent that the points 51 move in arcuate paths about the ring 53, which paths are concave toward the pivoted end of the spindle.

50 A collar 54 is carried by the spindle in a position to embrace the spring members 50, and is axially slidable in one direction to contract the members 50, or to permit them to expand when it is moved in the other direction. The collar 54 is carried by rods 55 passing through apertures 56 in the hollow frusto conical base 42. The ends of the rods 55 are adjustably secured by means of nuts 55a to another collar 57 slidably mounted on 55 the enlarged portion 58 of the stem 34.

It should be noted that the bifurcations 32 terminate in cam portions 60, so that when the stem 34 is swung outward from the position shown in Fig. 3, the cam portion 60 will 60 engage the collar 57 and urge it toward the

outer end of the spindle. This will cause the rods 55 passing through the spindle to push the collar 54 outwardly and contract the spring members 50, thus removing the spurs 51 from the inner surface of the cop and permitting it to be readily removed. Upon return of the parts to the position shown in Fig. 3, the spring action of the inclined members 50, bearing upon the conical interior surface 59 of the collar 54 will force the rods 55 to return the collar 56 to its original position. 75

The expansive force of the spring members 50 acting to grip the cop may be regulated by adjusting the nuts 55a. Obviously, 80 the fixing of the extreme position of the collar 54 closer to the free end of the spindle will decrease the engagement of the points 51 with the inner surface of the cop. 85

The embodiment of the invention shown in 85 Figs. 3 and 4 is adapted for use with cops of the cone type. However, the invention is also equally adapted for tubular cops, and embodiments of the invention for this purpose are shown in Figs. 5 to 9 inclusive. 90

Referring more particularly to Fig. 5, a stem 61 is provided in the place of the stem 34 shown in the modification previously described, and is integral with the enlargement 35 pivoted on the pin 36 mounted between the bifurcations 32 of the arm 13. The seat 37, spring 38 and adjusting bolt 39 are identical with those previously described. 95

Mounted on the stem 61 is a tubular spindle 62, one end of which is slotted as at 63, dividing the end of the spindle into a plurality of tongues 64. The outer surfaces of the tongues 64 are threaded or corrugated as at 65 and are normally flared outwardly as shown in Fig. 5, and provided with conical surfaces at their ends 66. The bore of the spindle 62 is enlarged at its outer end as at 67, forming a shoulder 68. A washer 69 secured to the outer end of the stem 61 by a machine screw 70, engages the shoulder 68 100 and secures the spindle 62 on the stem 61 for rotation thereon. 110

Mounted on the stem 61 between the spindle 62 and the head 35 is a collar 71 having a conical inner surface 72 adapted to slidably receive the conical surfaces 66 of the outer ends of the tongues 64, and a washer 74 is located between the collar 71 and the inner end of the spindle. 115

It will be obvious from an inspection of 120 Fig. 5 that when the stem is swung from the position shown in full lines to the position shown in dotted lines, the washer 74 engaging the inner surface of the collar 71 will ride along the cam surface 60 forcing the 125 conical surface 72 to ride over the conical ends 66, thus contracting the tongues 64. In this position the tubular cop 73 may slide over the spindle 62 so as to abut the outer edge of the collar 71. When the stem 61 is 130

swung back to the position shown in full lines, the tongues 64 will expand as the collar 71 rides off the cam 60, and the threads or corrugations 65 will grip the inner surface 5 of the tube 73 so that it will rotate with the spindle 62 for winding purposes.

The gripping force of the tongues 64 may be adjusted by the structure shown in Fig. 7. With this arrangement the bore 67 is threaded 10 to receive locking plugs 75 and 76. The washer 69 and screw 70 are omitted, and a filister headed screw 77 is substituted. When the plugs 75 and 76 are removed, the screw 77 may be unscrewed, which will permit the spindle 62 to move outwardly along 15 the stem 61. This will permit the tongues 64 to move further out along the surface 72 of the collar 71 and exert greater pressure on the inside of the tube 73. Obviously, tightening up the screw 77 will have the reverse effect. In either case if the adjustment is effected, the plugs 75 and 76 are threaded 20 into the bore 67 and securely lock the screw 77 in its adjusted position.

25 In the embodiment shown in Figs. 8 and 9, the gripping takes place at the outer end of the spindle. The spindle 80 is provided with an enlarged inner end 81 forming a shoulder 82 against which the tubular cop 30 abuts when it is mounted on the spindle. The outer end of the spindle 80 is slotted forming tongues 83 having threaded surfaces 84 and conical surfaces 85 at their outer ends, and normally flared outward from the 35 periphery of the stem 61. A collar 86 having a conical inner surface 87 is mounted on the stem 88 of a bolt 89, the inner threaded end of which is of reduced diameter to enter the tapped hole 90 in the outer end of the 40 stem 61. At the pivoted end of the stem 61, an L-shaped stop member 91 is provided, which is preferably though not necessarily formed of spring metal. One of the legs 93 of this member 91 is adapted to receive the 45 stem 61 within its slot and bear against the inner end 81 of the spindle 80 to prevent the spindle 80 from approaching too close to the pivoted joint or having too much play upon the stem 61 when the spindle is in running 50 position. The outer leg 97 of the member 91 is provided with a slot 98 which receives the pin 36 and is adapted to provide for limited movement of the member 91 upon the pin 36. The inner end of the slot 98 is 55 adapted to abut the pin 36 to prevent any further movement of the member 91 and spindle 80 toward the left than is shown in Figure 8.

When the spindle is swung outward, the 60 inner surface of the flange 93 rides on the cam surface 60 and bears against the end 81, urging the spindle 80 outward so that the conical ends 85 of the tongues 83 will be contracted by the conical surface 87 of the collar 86. This will permit a tube to slide over

the spindle 80 and abut against the shoulder 82. When the spindle is swung back to the position shown in Fig. 8, the spring action of the tongues 83 will cause them to expand and the surface 85 sliding against the surface 87 will urge the spindle inwardly on the stem 61 against the member 91. The corrugations 84 will then engage the interior surface of the tube and securely hold it on the spindle 80 for rotation therewith. In this form the bolt 89 is set up tight in the hole 90, so that it maintains a fixed position.

Having thus described the invention, what is claimed as new and desired to be secured by Letters Patent is:

1. In a cop winding machine having means for supporting a cop for winding when in one position and adapted to be swung to another position to permit the cop to be removed, the combination of a spindle having a plurality of spring members normally flared outwardly therefrom and adapted to engage the inner wall of a cop carried by said spindle, means for contracting said spring members to release the cop, and means for adjusting said contracting means to limit the gripping force of said members.

2. In a cop winding machine a spindle adapted to support a tubular cop for winding when in one position and to be swung to another position to permit the cop to be removed, said spindle having one end slotted, forming a plurality of tongues, said tongues being normally flared outwardly and corrugated for gripping the inner surface of the 95 cop, the ends of the tongues having cam surfaces, and a collar mounted coaxial with said spindle having a conical inner surface 100 adapted to engage the ends of said tongues to contract them for releasing the tubular 105 cop when the spindle is swung to doffing position.

3. In a cop winding machine, a pivoted stem, a tubular spindle journaled on said stem, said spindle having an enlarged inner 110 end forming a shoulder to receive the end of a tubular cop, the outer end of the spindle being slotted and expanded, forming a plurality of outwardly flared tongues, each of said tongues being corrugated to grip the 115 inner surface of the cop, and tapered at the outer end, a collar mounted at the outer end of said stem having a conical inner surface, a spring bearing on said enlarged inner end normally urging the tongues into the conical 120 collar, and a cam actuated by moving the stem about its pivot for moving said spindle outwardly on said stem to contract the tongues and release the spindle.

In testimony whereof I hereunto affix my 125 signature.

CHARLES K. DUNLAP.
